Primary Examiner — Robert M. Spear(74) Attorney, Agent, or Firm — Gulf Coast Intellectual Property Group(57) CLAIM

The ornamental design for a therapeutic animal jacket, as shown and described.

DESCRIPTION

FIG. 1 is a right side elevational view of a therapeutic animal jacket, showing my new design;

FIG. 2 is a left side elevational view thereof;

FIG. 3 is a front elevational view thereof;

FIG. 4 is a rear elevational view thereof;

FIG. 5 is a top plan view thereof; and,

FIG. 6 is a bottom plan view thereof.

The broken line showing of a dog depicts environment and forms no part of the claim.
